TENT

Frank M. Powers, River Forest, Ill., and Thomas C. Powers and David W. Powers, Philadelphia, Pa., assignors to Powers & Company, a partnership

Application October 29, 1948, Serial No. 57,332

14 Claims. (Cl. 135—3)

1

This invention relates to a tent, and particularly to a support for the tent fabric that is readily assembled and disassembled, and that maintains a rigid structure when assembled in combination with the tent fabric.

The subject of this invention is particularly useful in the manufacture of children's play tents, as the tent can be assembled and disassembled quite readily, and when disassembled occupies a small space for storage.

The new tent structure comprises broadly horizontal frame means having the outline of the adjacent portion of the tent, tent fabric engaged by the horizontal frame means, and an upright support member engaging a part of the frame means and tensioning the tent fabric to form a rigid structure. The support member is horizontally slidable on a part of the frame means engaged by it to release the tension on the tent fabric and collapse the tent for storage.

The tent fabric need not be disengaged from the frame means unless desired, and the tent may be reassembled merely by returning the support member to its upright, supporting position.

The invention will be described as related to the embodiments set out in the accompanying drawings. Of the drawings Fig. 1 is a perspective view of a circus type child's play tent with the tent fabric indicated by dotted lines; Fig. 2 is a vertical section taken along line 2—2 of Fig. 1; Fig. 3 is a perspective view of a second embodiment of the invention; Fig. 4 is a perspective view of a third embodiment of the invention; Fig. 5 is a perspective view of the framework for a fourth embodiment of the invention; Fig. 6 is an elevation of a supporting rod for said fourth embodiment partially in section; and Fig. 7 is a fragmentary elevation showing the bottom portion of the framework in folded position.

The tent shown in Figs. 1 and 2 comprises a bottom member 10 made of a rod in the form of a closed figure having the shape of the bottom of the tent, and with two transverse rods 11 near each end of the bottom member 10, an intermediate member 12 similar in shape to the bottom member 10 but of smaller size, a pair of upright support members 13 with one of said members at each end of the tent and engageable with a transverse rod 11, and the tent fabric 14 stretched over the bottom member 10, intermediate member 12 and upright members 13 to form a rigid structure. The intermediate member 12 and the upright member 13 are made of rods. The bottom member 10 and intermediate member 12 provide horizontal frame means for the tent.

2

The transverse rods 11 are preferably welded at their ends to the bottom member 10. The upright members 13 have their bottom ends formed with an arcuate surface 15 so that they will fit over the transverse rods 11. Each transverse rod preferably has an upwardly open, generally U-shaped bend, forming a slotlike deformity, as indicated at 16, to help hold the upright member in place. The top ends of the upright members are provided with spikes 17 that pass through holes 18 in the tent fabric. These holes are reinforced by patches 19 or metal eyelets.

The bottom of the tent fabric 14 may be sewed to the bottom member 10 as indicated at 20. This bottom portion may be tied to the bottom member, however, if desired.

The intermediate member 12 is preferably tied to the tent fabric as by means of spaced tie strings 21.

20 The embodiment shown in Fig. 3 is similar to that in Figs. 1 and 2 except that here the tent is a wall tent, and the bottom member 110 and the intermediate member 112 are both rectangular. When the tent is assembled the upright support members 13 are preferably placed outside of the intermediate member 112 so as to give stability to the tent structure. Again, the bottom member 110 and intermediate member 112 provide horizontal frame means.

25 In the embodiment shown in Fig. 4 the bottom member 210 provides horizontal frame means which is substantially square, and there is only one transverse member 211 substantially bisecting opposite sides of the bottom member 210.

30 In the embodiment shown in Figs. 5 to 7 the fabric is not shown and the framework comprises a bottom oval portion 25, a top oval portion 26 of similar shape but slightly smaller, spaced supporting legs 27, and an arcuate bar 28 extending from end to end of the top oval 26. The oval portions 25 and 26 provide horizontal frame means. Each supporting leg 27 is made of two bars 29 and 30 hinged together by means of a pin 31. The top of bottom bar 30 extends beyond the bottom of top bar 29 with the pin 31 extending through the bottom portion of top bar 29 and through bar 30. The two bars are held in extended relationship to form one continuous leg by means of a slidably sleeve 32. When the sleeve 31 is in place, as shown in Fig. 6, it embraces the top of bottom bar 30 and the bottom of top bar 29. When the sleeve is moved upwardly the two bars may be folded around their hinge pin as shown in Fig. 7.

35 40 45 50 55 55 Each leg 27 has its bottom end bent to form an

eye 33 extending around a curved section 34 of the bottom oval member 25. Thus each leg can be folded down as indicated in Fig. 7. The top of each leg is bent to provide loop 35 open at the top. The loops support the top oval member 26; but the leg may pivot about its eye 33 so that the loop 35 slides out of engagement with the member 26 to permit collapse of the tent structure. Folding the legs 27 about the pins 31 makes them more compact for storing the tent structure.

The arcuate bar 28 has loops 36 formed in its two ends with these loops passing around raised curved sections 37 of the top oval member 26. This permits folding of the arcuate section 28 onto the oval member 26.

Each illustrated embodiment includes horizontal frame means, a fabric tent engaged by the horizontal frame means, and an upright support member engaging a part of the horizontal frame means and tensioning the fabric tent to form a rigid structure. The support member slidably engages a part of the horizontal frame means so that it may be moved to a collapsed position to release the tension on the fabric tent.

Having described our invention as related to the embodiments set out in the accompanying drawings, it is our intention that the invention be not limited by the details of description unless otherwise specified, but rather be construed broadly within its spirit and scope as set out in the accompanying claims.

We claim:

1. A tent structure comprising a rigid bottom member including a round bar forming a closed figure having the outline of the bottom of the tent, an upright member comprising a round bar engageable with the bottom member at its lower end and with the tent fabric at its upper end, and an intermediate member including a round bar forming a closed figure having the outline of an intermediate section of the tent with the intermediate member being engageable with and supported by the tent fabric, said members being adapted to form a rigid structure when assembled with the tent fabric, and said lower end of the upright member being provided with an arcuate surface adapted to straddle the bar of the base member when the structure is assembled.

2. In a tent structure having a fabric tent, a rigid bottom member of round metal rod means, the outer perimeter of which forms a closed figure having the outline of the bottom of the tent, and an upright member having an arcuate portion at its lower end to loosely and slidably engage said round metal rod means, said members being adapted to engage the fabric tent to produce a rigid structure and said upright member being held in upright position solely by engagement with the fabric tent.

3. In a tent structure having a fabric tent, a rigid bottom member including a bar of substantially circular cross section which forms a closed figure having the outline of the bottom of the tent, and an upright member of substantially circular cross section which has at its lower end an arcuate surface adapted to straddle and loosely and slidably engage the bar of the base member when the tent structure is assembled, said members being adapted to engage the fabric tent to form a rigid structure, and said upright member being held in upright position solely by engagement with the fabric tent.

4. In a tent structure having a fabric tent, horizontal frame means including a bottom frame member having the shape of the bottom of the

7 fabric tent and an intermediate frame member having the shape of an intermediate portion of the fabric tent, said frame members being engaged with the fabric tent, a plurality of support members engaging both of the frame members and horizontally slidably on one of said members for movement between an upright supporting position in which it tensions said fabric tent to form a rigid structure, and a collapsed position, 10 whereby said tent structure may be collapsed while maintaining the engagement between said fabric tent and said horizontal frame means.

5. The tent structure of claim 4 in which the support members comprise two pivotally joined 15 pieces and means for detachably securing said pieces in extended position.

6. The tent structure of claim 4 in which the support member has an eye at one end pivoted on a frame member and an arcuate portion at the 20 other end slidably engaging the other frame member.

7. The tent structure of claim 4 in which a supporting member is provided on the top member extending from opposite sides thereof for supporting the tent fabric.

8. The tent structure of claim 4 in which a supporting member is provided on the top member extending from opposite sides thereof for supporting the tent fabric, said supporting member being hingedly attached to said top member so as to be foldable into substantially the same plane as the top member.

9. In a tent structure having a fabric tent, horizontal frame means having the outline of the adjacent part of the fabric tent and engaged therewith, and a support member having an end engaging a part of said frame means and horizontally slidably thereon for movement between an upright position in which it tensions said 35 fabric tent to form a rigid structure, and a collapsed position, whereby said tent structure may be collapsed while maintaining the engagement between said fabric tent and said horizontal frame means.

45 10. The tent structure of claim 9 in which the horizontal frame means includes a bottom frame member having the outline of the bottom of the tent and provided with an upwardly facing shallow slotlike deformity, and the base of the support member is slidable on said bottom frame member and engages said deformity so as to be locked in upright position.

11. A tent structure comprising, in combination: a horizontal bottom frame having the outline of the bottom of the tent; a support member having an end slidably engaging a part of said bottom frame for movement between an upright supporting position and a collapsed position; a fabric tent engaged by said horizontal bottom 50 frame and tensioned by said support member in its upright position to form a rigid, collapsible structure; and an intermediate frame member having the outline of an intermediate part of the tent, said intermediate frame member being supported by the fabric tent.

12. A tent structure comprising, in combination: a bottom frame member of stiff wire which has the outline of the bottom of the tent and is provided with a cross bar having a short, upwardly open, U-shaped bend; a support member slidably supported on said cross bar for movement between an upright supporting position and a collapsed position, said support member having an arcuate lower end which spans the cross 60 bar and engages said U-shaped bend in support-

ing position; and a fabric tent engaged by said bottom frame member and tensioned by said support member in its upright position to form a rigid, collapsible structure.

13. A tent structure comprising, in combination: a horizontal bottom frame member having the outline of the bottom of the tent and having an integral cross bar extending from side to side thereof; a fabric tent having its lower end engaged by said bottom frame member; and an upright member having its base supported on said cross bar and horizontally slidably thereon for movement between an upright position in which it tensions said fabric tent to form a rigid structure, and a collapsed position, whereby said tent structure may be collapsed while maintaining the engagement between said fabric tent and said horizontal frame means.

14. A tent structure comprising, in combination: a rigid, uncollapsible bottom member hav- 20

ing the outline of the bottom of the tent; a fabric tent having its bottom portion permanently secured to said bottom member; and a support member having its base engaging a part of said bottom member and horizontally slidably thereon for movement between an upright supporting position in which it tensions said fabric tent, and a collapsed position.
